[57] CLAIM

The ornamental design for a handle bar support rod for shopping cart, as shown and described.

DESCRIPTION

FIG. 1 is a side elevation view of a handle bar support rod for shopping cart showing my new design. The broken lines showing of environmental structure are for illustrative purposes only and form no part of the claimed design;

FIG. 2 is an enlarged front elevation view thereof;

FIG. 3 is an enlarged rear elevation view thereof;

FIG. 4 is an enlarged bottom plan view thereof.

U.S. Patent
